UNITED STATES PATENT OFFICE.

JOSEPH PFEUFER, OF DUDELINGEN, NEAR LUXEMBURG, GERMANY.

BRUSHING APPARATUS FOR WASHING THE HUMAN BODY.

Application filed August 24, 1925. Serial No. 52,092.

This invention relates to a brushing apparatus for washing the human body. The apparatus is shown, by way of example, on the accompanying drawing, in which

5 Fig. 1 shows the apparatus in side elevation,

Fig. 1^a shows the rollers guided on a U-bar and

10 Fig. 1^b shows the rollers guided on a double I-bar.

Fig. 2 in rear elevation,

Fig. 3 in plan view and

Fig. 4 shows the brush in side elevation.

The apparatus consists of a vertical U-bar

15 1 and of horizontal arms 2, 3 fixed on the upper and lower ends of said bar. A guide piece 4 is movably guided by means of rollers 7, 8, 9 on said U-bar 1. On the guide piece 4 a blade spring 6 is fixed which carries a brush c. A string 10 attached to the upper end of the guide piece 4 is guided over rollers 11, 12 and attached at the other end to a counter-weight 13. To the bottom end of the counter-weight 13 a spiral spring 14

20 is attached so that it can be easily hooked on and off. A string 15 attached to the lower end of spiral spring 14 is guided over rollers 16 and 17 and attached at the other end to the bottom end of guide piece 4. The horizontal arm 2 is fixed on the U-bar 1 by means

25 of screws so that it can be easily removed and fixed on another apparatus. The arm 2 may be composed of two band irons on which the rollers 11 and 12 are mounted.

30 The U-bar 1 and arm 3 are mounted on the base plate 18.

Instead of the U-bar a double I-bar might be used.

If necessary the arms 2 and 3 may be further supported, these additional supports would however have to be arranged outside the rollers 12 and 16.

The operation of the apparatus is as follows:—

45 The person who wants to use the apparatus stands between the counter-weight 13 and the brush c, back turned towards the brush c. He moves the counter-weight 13 up and down with the aid of the string 10

50 and the brush c executes the same movements as the counterweight in opposite directions.

To brush the front part of the body the person turns round and moves the brush up and down by means of handles d and e (Fig. 2) fixed at the right and left of the guide 55 piece 4. The blade spring 6, on which the brush c is fixed, is fixed on the guide element 4 by means of pivotal links f and g. The outer ends of links f and g are connected with one another by a spiral spring h.

This arrangement serves to account for the unevenness of the human body and to facilitate the up and down movement of the brush on the body.

When the body presses against the brush 65 the blade spring 6 is stretched so that the brush yields and adopts the position shown in Fig. 4 in dash lines, the links f and g being at the same time swung outward. When the pressure of the body ceases or decreases the blade spring assumes the former 70 position and the spiral spring h brings the links f, g back into the normal position.

The brush may be covered by a cover adapted to be buttoned on.

75 I claim:—

1. A brushing apparatus for washing the human body comprising in combination an upright consisting of a U-bar, a guide piece movably mounted on said upright, rollers on 80 said guide piece rolling on said U-bar, a brush elastically mounted on the inner surface of said guide piece, a counterweight, a string connecting said counterweight with said guide piece, and rollers over which 85 said string is guided.

2. A brushing apparatus for washing the human body comprising in combination an upright consisting of a U-bar, a guide piece movably mounted on said upright, rollers on 90 said guide piece rolling on said U-bar, two links pivotally mounted one at either side wall of said guide piece, a spiral spring connecting the front ends of said links the one with the other, a blade spring fixed on 95 the front ends of said links, a brush fixed on said blade spring, a counterweight, a string connecting said counterweight with said guide piece, and rollers over which said string is guided.

100 In testimony whereof I affix my signature.

JOSEPH PFEUFER.
